UNITED STATES PATENT OFFICE.

WILLIAM H. BURK, OF ST. LOUIS, MISSOURI, ASSIGNOR TO CORRUGATED BAR COMPANY, OF ST. LOUIS, MISSOURI, A CORPORATION OF MISSOURI.

CONCRETE FLOOR CONSTRUCTION.

1,039,895.

Specification of Letters Patent.

Patented Oct. 1, 1912.

Application filed June 17, 1910. Serial No. 567,348.

To all whom it may concern:

Be it known that I, WILLIAM H. BURK, a citizen of the United States, and a resident of the city of St. Louis and State of Missouri, have invented a new and useful Improvement in Concrete Floor Constructions, of which the following is a specification.

My invention relates to floor constructions and more particularly to reinforced concrete floor constructions. It has for its principal objects to economize in labor and material, to dispense with girders, and to secure maximum head-room.

The invention consists principally in forming the entire floor as a grating consisting of two series of parallel beams at right angles to each other, the beams being of uniform depth but of varying width so that in load-sustaining capacity and resistance to stress they will vary in accordance with the loads and stresses imposed upon them by their position in the structure and in their relation to the supports.

It also consists in the constructions and arrangements of parts hereinafter described and claimed.

In the accompanying drawings which form part of this specification and wherein like symbols refer to like parts wherever they occur, Figure 1 is a plan of a floor embodying my invention; Fig. 2 is a cross section thereof on the line 2—2; Fig. 3 is a cross section of a floor provided with a wooden floor covering; Fig. 4 is a plan of a modified construction of a floor embodying my invention; and Fig. 5 is a cross section on the line 5—5 of Fig. 4.

In the construction illustrated in the accompanying drawings, the columns 1 are located to form rectangular bays. Extending from column to column around four sides of a bay are beams 2 of reinforced concrete; and parallel with each of these marginal beams are a plurality of beams 3 arranged to intersect with each other, all formed of reinforced concrete and preferably monolithic with the marginal beams 2 and the columns 1.

According to my invention the load-sustaining capacity or strength of the portion of the bay adjacent to the supports is required to be greater than is required of the middle portion of the bay; and this condi-

tion can be satisfied in various ways. For instance, as illustrated in Figs. 1 to 3, inclusive, of the drawings, the beams in the outer or marginal portion of the bay may be made wider and of relatively greater strength and load-sustaining capacity than the beams in the middle portion of the bay. In this case, all of the beams are of even depth and they are preferably spaced at equal intervals apart, in order that tiles 4 of uniform size may be used therewith. In this construction it is theoretically desirable to make each beam in succession narrower than the one next adjacent to it outwardly therefrom; but for practical purposes, the innermost beams may be made of the same size.

In order to take care of the shearing stresses adjacent to the column, it is preferable to form the corner portions 5 of the bays solid and to reinforce the same in some suitable manner.

In the practical building of my construction, a flat or smooth-surfaced falsework or centering is erected. The metal reinforce for the respective beams is then positioned above the falsework, and hollow tiles or blocks or other fillers 4 are then set on the falsework in proper position with respect to the metal reinforce. The concrete is then filled in and permitted to set and harden, being preferably monolithic with the columns and the adjacent bays. By reason of the centering being flat, the cost of building is comparatively small, and the bay is of even depth throughout. The construction dispenses entirely with main girders and gives a maximum head-room entirely free from obstruction.

In the construction above described, the upper surface of the bay consists partly of the tops of the concrete beams and partly of the tops of the tiles. As illustrated in Fig. 3, this construction may be covered with a layer of cement; or it may be covered or finished in any other desirable manner.

The construction may also be varied by the use of tiles or filler blocks of varying depth as shown in Fig. 5, so as to allow the upper part of the beams to be connected with a slab of concrete of such thickness as to secure the necessary compressive area in the concrete beams that are most heavily stressed.

Obviously, the constructions herein described admit of considerable modification without departing from my invention. Thus, all of the beams may be of uniform width, but reinforced proportionately to the stresses computed for the region in which they are located. So, too, the beams may be of uniform strength but spaced at increasing intervals toward the middle of the bay. It is also noted that the bays or slabs may, obviously, be supported at two opposite or all four sides by walls instead of columns at the corners thereof.

What I claim is:

15. 1. In a system of floor construction, supports arranged to divide the floor into panels and a composite tile and concrete slab resting thereon, said slab comprising series of intersecting reinforced concrete beams of different widths crossing the floor panels intermediate the supports, the wider beams being disposed adjacent to the margins of the panels.
20. 2. A monolithic reinforced concrete building construction comprising columns and a plurality of floor panels supported thereby, each panel having a plurality of groups of parallel beams arranged in two intersecting series, said beams being all of substantially even depth and each of said series comprising beams of different widths, the beams crossing the middle portion of the panel being narrower than the marginal beams.
25. 3. A rectangular floor panel comprising a series of reinforced concrete beams parallel with one of its sides and a second series of reinforced concrete beams intersecting those of the first series at right angles, each of said beams being of uniform depth and width but the width of some beams differing from the width of other beams of the same series, the wider beams of each series being arranged near the margins of the panel.
30. 4. In a building construction, floor panels and supports therefor, said panels comprising series of intersecting reinforced concrete beams of even depth, the beams decreasing respectively in width progressively from the marginal edges toward the middle of the panel.
35. 5. A system of floor construction comprising columns and rectangular panels, each of said panels comprising a series of reinforced concrete beams crossing the same intermediate said columns and parallel with two of its sides, said beams being of substantially even depth but the beams adjacent to the margins of the panel being wider than the inner beams.
40. 6. A system of floor construction comprising columns and rectangular panels, said panels comprising a series of reinforced concrete beams crossing the same intermediate said columns and parallel with two of its sides, each of said beams being of substan-

tially uniform section throughout but successive beams being of different sectional area, the beams of greater sectional area being arranged adjacent the margins of the panels.

70. 7. A system of floor construction comprising supports and rectangular panels resting thereon, each panel comprising series of intersecting reinforced concrete beams parallel with two of its sides, said beams being of even depth but respectively of a width substantially proportional to the distance from the middle thereof to the center of the panel.

75. 8. A composite tile concrete floor slab and supports therefor, said supports dividing the floor into bays, tile blocks having their bottoms flush with the lower surface of the slab spaced in intersecting rows across said bays, said tile blocks being of different heights, the spaces between the marginal rows of blocks in said bays being greater than the spaces between the central rows, and concrete filling in the spaces between and over said tile blocks, said concrete filling being flush with the upper surface of the slab and constituting intersecting series of spaced beams lying partly above and partly between said tile.

80. 9. A rectangular floor slab comprising series of intersecting reinforced concrete beams parallel with two of its sides, the amount of reinforcement in the beams of each series being greater in some than in others so that the beams are of varying strength, the beams of greater strength being arranged adjacent to the margins of the slab.

85. 10. A rectangular floor slab comprising series of reinforced concrete beams parallel with each of its sides, said beams intersecting at angles to each other throughout the slab, the amount of reinforcement in the beams being greater in some than in others so that the beams are of varying strength, the beams of greater strength being arranged adjacent to the margins of the slab and the inner beams decreasing successively in strength.

90. 11. A system of construction comprising supports and rectangular bays supported thereby, each bay comprising series of intersecting reinforced concrete beams parallel with two of its sides, said beams being of substantially even depth but the amount of reinforcement in the beams being greater in some than in others so that the beams are of varying strength, and arranged in the order of decreasing strength inwardly from the margins of the slab, and filler blocks fitted tightly between the adjacent beams.

95. 12. A system of tile concrete floor construction comprising supports and rectangular tile concrete panels supported thereby, each panel comprising separated rows of spaced tiles and series of intersecting reinforced concrete beams filling the spaces

between said tiles, the tiles in each row being spaced apart at different distances; the wider spaces being near the ends of the row.

13. A system of floor construction comprising supports and rectangular reinforced concrete panels supported thereon, said panels comprising a series of beams parallel with two of its sides, said beams being provided with reinforcing bars in their lower regions, the number of bars in the respective beams being varied, and there being fewer bars in each successive beam, proceeding inwardly from the marginal portions of the panels, and filler blocks fitted in the spaces between the beams and integral with said beams.

14. A system of floor construction comprising supports and rectangular panels resting thereon, each panel comprising a plurality of intersecting beams crossing the same intermediate said supports and arranged with their lower surfaces in the same plane, reinforcing rods arranged in the lower regions of said beams, the amount of reinforcement in the beams being greater in the beams adjacent the margins of the panels than in the beams remote from the margins of the panels, the said beams being connected with a slab or body of concrete built integral therewith and acting as part of said beams for the resistance of compressive stresses, said slab being thicker in some portions of said panels than in other portions thereof.

15. A system of floor construction comprising supports and a composite tile concrete floor slab resting thereon, said slab comprising a plurality of concrete beams of

different widths arranged parallel to the edges of the bays defined by the supports, 40 said beams being arranged progressively in order of decreasing width from the margins toward the middle of said bays, tile blocks of different depths fitted between adjacent beams, and concrete filling over some of said 45 blocks and integral with said beams.

16. A composite tile concrete floor panel comprising a plurality of tile blocks arranged in intersecting series of spaced parallel rows extending across said panel, the 50 rows of tile near the margins of the panel being spaced farther apart than the rows of tile crossing the middle of the panel, the spaces between said tile being filled with concrete forming intersecting parallel ribs 55 of varying widths, the width of said ribs varying with the changes in the spacing apart of the rows of tile blocks adjacent thereto respectively.

17. A system of floor construction comprising columns and quadrangular floor slabs, said slabs comprising series of embedded reinforced concrete ribs, each series being parallel with one of the sides of a slab and crossing the same intermediate said columns, and rows of spaced tiles of different 60 sizes fitted between said ribs, the tiles in the marginal rows being uniform in size and 65 larger than the tiles in the central portions of the slabs.

Signed at St. Louis, Missouri, this 14th day of June, 1910.
